J. M. Bachelor
Thin Coupling

No 16,577 Patented Feb. 10, 1857.

UNITED STATES PATENT OFFICE.

J. M. BATCHELOR, OF FOXCROFT, MAINE.

MODE OF ATTACHING THILLS TO SLEIGHS.

Specification of Letters Patent No. 16,577, dated February 10, 1857.

To all whom it may concern:

Be it known that I, J. M. BATCHELOR, of Foxcroft, in the county of Piscataquis and State of Maine, have invented a new and improved mode of attaching thills to sleighs, whereby the thills are rendered adjustable, so that they may be secured directly in front or in line with the sleigh or at points at either side of the center of the sleigh; and I do hereby declare that the following is a full, clear, and exact description of the same, reference being had to the annexed drawings, making a part of this specification, in which—

15 Figure 1, is a side view of a sleigh with the thills attached to it according to my improved mode. The sliding and grooved bars which constitute my improvement, being bisected transversely as indicated by the line 20 x, x , Fig. 2. Fig. 2, is an inverted plan of the same. Fig. 3, is an enlarged transverse section of the sliding and grooved bars, y, y , Fig. 2, indicating the plane of section.

25 Similar letters of reference indicate corresponding parts in the several figures.

This invention relates to an improved mode of attaching thills to sleighs, whereby the thills are rendered capable of being adjusted either directly in front or in line with 30 the center of the sleigh or at points at either side of the center of the sleigh, so that the horse and the sleigh may, in all cases, be so placed relatively with each other as to conform to the track of the road.

35 The invention consists in attaching the thills to a sliding bar which is fitted within a grooved bar, the sliding bar being secured at desired points within the grooved bar, by means of a spring which catches into notches 40 or recesses in the edges of the grooved bar, as will be hereinafter fully shown and described.

To enable those skilled in the art to fully understand and construct my invention, I 45 will proceed to describe it.

A, represents a sleigh, and B represents a cross bar secured to the front parts of the runners C.

To the under side of the bar B, a grooved 50 plate or bar D, is attached by screws a . This plate or bar D, may be constructed of metal and the groove may be formed by swaging or bending down a lip b, b' , one at each side of the plate or bar, or the plate 55 may be cast with the lips upon it. These

60 lips b, b' , are bent or curved downward and inward, as more particularly shown in Fig. 3, so that they may receive and sustain a bar E, which bar is allowed to slide freely back and forth between the lips b, b' , and underneath the bar D. To each end of the bar E, a curved arm F, is attached. These arms project outward at right angles with the bar E, and each arm has a journal or pin c , at its outer end on which journals or 65 pins the goose-necks d , of the thills G, are placed. To the under side of the bar E, a spring H, is attached. This spring is merely a flat plate one end of which is secured to the bar E. The opposite end of the spring H, has a lip or projection e , on it at right angles with the plate or spring. This lip or projection extends over the lip b' , at the inner edge of the bar D, and the lip b' , has notches or recesses f, f', f'' , made 70 in it at proper points, as shown in Fig. 2. The lip or projection e , on the spring H, secures the bar E, and thills G, in a position either directly in front or in line with the sleigh or at points at either side of the 75 center of the sleigh. When the lip or projection e , is in the notch or recess f' , as shown in black, Fig. 2, the thills will be directly in front or in line with the sleigh. When the lip or projection is in the notch or recess f , as shown in red, the thills will be 80 at one side of the center of the sleigh, and when the lip or projection is fitted in the notch or recess f'' , the thills will be secured 85 at the opposite side of the sleigh.

90 Thus it will be seen that the thills, by merely raising the lip or projection e , on the spring H, may be readily adjusted either in line with the center of the sleigh or at points at either side of the center of the 95 sleigh.

In most parts of the country, teams or two-horse sleighs are generally used, and the roads consequently have a ridge of snow directly in the center—the ridge being 100 formed by the horses beating down the snow at each side of the road or track. A single horse sleigh having its thills in line with the sleigh cannot well be used when roads are in this condition, as the horse 105 would be obliged to travel on the ridge at the center of the road or track and consequently would be liable to slip. By my improvement, the thills may be moved to either side of the sleigh to allow the horse to travel 110

at one side of the central ridge previously alluded to, and at the same time allow the sleigh to be in the direct track at the center of the road. Roads that are much used or 5 traveled upon, of course, are not liable to this objection, as the ridge is prevented from being formed by the constant crossing and recrossing of the sleighs. The thills may then be placed in line with the sleigh. 10 I am aware that thills have been previously attached to sleighs in such a manner that the thills may be adjusted or moved to either side of the sleigh, but the modes previously adopted have been complicated and 15 the thills could not be adjusted without considerable difficulty. My improvement is extremely simple, may be applied to sleighs at

a small cost and the thills may be adjusted with the greatest facility.

Having thus described my invention what 20 I claim as new and desire to secure by Letters Patent, is—

Attaching the thills G, to the bar E, which bar is fitted within a grooved bar D, attached to the sleigh, the bar E, being allowed to slide within the grooved bar D and secured at the desired points by the spring catch H substantially as described for the purpose set forth.

J. M. BATCHELOR.
